UNITED STATES PATENT OFFICE.

AUTHOR W. GOETZ, OF CHICAGO, ILLINOIS.

BATH-FIXTURE VALVE.

Application filed January 18, 1924. Serial No. 687,141.

To all whom it may concern:

Be it known that I, ARTHUR W. GOETZ, a citizen of the United States, residing at Chicago, in the county of Cook and State of Illinois, have invented a certain new and useful Bath-Fixture Valve.

This invention pertains more particularly to a new and useful interchangeable working unit particularly adapted for bath fixtures and shower valves. As is well known in the art, the working units of valves of this character in use are subjected to tremendous torque and other strains both when turning the stem down too tightly or releasing when it has become tightly set, due to expansion or other causes. Not infrequently under such conditions, parts of the old cast structures generally used prior to my invention were broken and the valve rendered useless. Another disadvantage of the cast working units in use prior to my invention, was the difficulty in properly alining one part with respect to another owing to the fact that it was impossible in actual practice, to maintain uniformity in the manufacture or casting of these parts. Moreover, they were very brittle and incapable of giving slightly under great strain without breaking particularly the stem, did not machine well, and did not possess sufficient tensile strength to properly withstand the tremendous strains and stresses imposed thereon. Further, the threads cut in the cast bonnet on which the stem turned were easily broken and lasted but a comparatively short time under constant use. It is, therefore, an object of my invention to provide an interchangeable working unit for such valves in which the entire working unit, which consists of the stem, stuffing gland, bonnet and escutcheon holder is made from a solid brass rod, instead of castings, as was the practice heretofore, and one which will entirely overcome all the disadvantages of the old cast construction, and one which can be made absolutely true in all cases, to insure proper alignment and working of parts, and adds materially to the longevity of the device. It is a further object to provide a unit of this type which can be readily and quickly adjusted to accommodate walls or partitions of varying thickness. It is a further object to provide a resilient stem which will give slightly under abnormal strains.

The above and other features of novelty, advantages and capabilities will become ap-

parent from a detailed description of the accompanying drawings, in which I have illustrated one form of my invention, but the construction there shown is to be understood as illustrative only, and not as defining the limits of my invention.

In the drawings:

Fig. 1 is a view partly in section, of a valve body with the working unit in elevation, illustrating one form of my invention.

Fig. 2 is a sectional view of the same showing a portion of the valve stem in elevation.

Fig. 3 is a sectional view of a portion of the valve body showing my interchangeable working unit removed and the valve body closed with a screw-threaded plug, and,

Fig. 4 is a diagrammatic view illustrating a piece of solid brass rod and showing in dotted lines the form taken after being machined to produce the bonnet of my working unit.

Referring to the drawings in detail, 10 indicates the valve body which, in practice and when installed extends through a wall or partition, the head of which is connected with suitable screw-fitted pipes 11 and 12 leading to and from a source of hot and cold water. The neck portion 13 which extends through the wall or partition, in practice, is, near its outer or free end, interiorly provided with $3/4$ " iron pipe threads 14. The working unit comprises a valve stem 15, 80 swivel disc 28, bonnet 16, adjusting and stuffing gland, 17, and an adjustable escutcheon holder 18, all of which parts are cut from solid brass rods of the proper diameter or size and then machined to the forms shown. The bonnet whose outer end terminates in a hexagonal flanged head, 20, adapted to tightly engage the outer end of the valve body when properly screwed down, is provided with $3/4$ " pipe threads, designed 85 to register with the threads on the interior of the valve body. Extending through the bonnet is the solid brass rod valve stem 15 which, near its inner end, is provided with acme threads, 21, which turn in similar threads 22, formed on the interior of the bonnet. The bonnet, 16 is provided on the interior, intermediate its ends, with an integral inwardly extending flange 23, and adjacent this flange and surrounding the stem is a 90 suitable packing 24. The bonnet at its outer end is interiorly provided with $3/8$ " pipe

threads. The combined adjusting and stuffing gland 17, is provided with two extensions 17^a and 17^b of unequal length, the said extensions being provided throughout 5 the entire length with $\frac{3}{8}$ " pipe threads. Either end of this nut is designed to screw into the outer end of the bonnet 16, as desired, and into engagement with the packing 24 to compress the same for forming a 10 water tight fit around the stem 15. The cup shaped escutcheon holder 18, is interiorly threaded throughout its length with $\frac{3}{8}$ " pipe threads and is adapted to telescopically screw on to either extension of the gland 17 15 for holding the escutcheon 25 properly in place and protect the threads on the gland. As it is desirable in practice, that the inner edge of the escutcheon holder be screwed up 20 against the gland 17, as shown in Fig. 2, this gland is made reversible with respect to the bonnet and escutcheon holder. Therefore, by simply reversing the gland the parts can be readily and quickly adjusted to suit 25 the varying conditions in use. The outer end of the resilient valve stem is provided with two transverse screw-threaded openings 26 at right angles, to receive the usual china index handle.

By providing the valve body with $\frac{3}{4}$ " pipe threads, it enables the plumber to insert an ordinary $\frac{3}{4}$ " black iron plug 27 in the valve body opening, thus leaving the stem and china intact in a box in the store room until such time as they are ready to 30 turn over the job complete for architectural approval. With the ordinary valve heretofore on the market, this was not possible and frequently, where the working unit of the valve was put in place before the job was 35 completely finished, they were damaged or broken by careless workmen standing on the stem, or from other causes. The resilient valve stem is cup shaped at its inner end and has rotatably mounted therein a disk 40 28 to which is secured by means of a screw 45 29, a suitable washer 30, adapted to co-operate with the outlet or port of the valve body when the stem is operated in the usual way. The disk 28 is held in the stem by 50 bending the inner end of the stem inwardly around the neck 28^a of the disk.

In manufacturing the working unit, that is the valve stem, escutcheon holder, adjusting and stuffing gland, bonnet and disk, I 55 take solid brass rods of proper dimension, which rods are cut into pieces of the proper length, then turned down to approximate the form of the finished article, and the threads herein described are then cut on the 60 parts thus formed. The exposed portions are then polished and plated. Due to the fact that they are constructed of solid brass rods, they can be polished and plated much easier than the old cast parts.

65 From the description thus far it will

readily be seen that I have produced a working unit which possesses to the fullest extent all of the features heretofore mentioned as well as many other inherent advantages.

Having thus described my invention, I claim:

1. In a bath fixture or shower valve, the combination of a valve body having a neck 70 interiorly provided, at its outer end, with $\frac{3}{4}$ " iron pipe threads, a bonnet constructed of solid brass, adapted to engage said threads and screw into said valve body, a valve stem constructed of solid brass and having acme screw threads adapted to turn 75 on acme screw threads within said bonnet, a stuffing gland constructed of solid brass provided with extensions of unequal length, having $\frac{3}{8}$ " pipe threads thereon, adapted to screw into said bonnet, a cup shaped escutcheon holder constructed of solid brass adapted to telescopically screw on to either 80 end of said stuffing gland, substantially as and for the purpose set forth.

2. In a bath fixture valve, the combination of a valve body having a neck interiorly provided, at its outer end, with threads, a bonnet constructed of solid brass, adapted to engage said threads and screw into said valve body, a valve stem constructed of 90 solid brass and having acme screw threads adapted to turn on acme screw threads within said bonnet, a stuffing gland constructed of solid brass provided with extensions of 95 unequal length, adapted to screw into said bonnet, a cup shaped escutcheon holder constructed of solid brass adapted to telescopically screw on to either end of said stuffing gland and a disk rotatably clamped in the inner end of said stem substantially as and for the purpose set forth.

3. In a working unit for bath fixture valve the combination of a brass bonnet, a brass rod valve stem, and a brass reversible adjusting and stuffing gland provided with 100 extensions of unequal length, substantially as and for the purpose set forth.

4. In a valve of the class described, the combination of a valve body having a neck 110 interiorly provided at its free end, with threads, a bonnet provided with threads adapted to engage said threads and screw into said valve body, a valve stem constructed of solid brass extending through said bonnet, and adapted to turn on acme threads cut therein, an adjusting and stuffing gland provided with extensions of unequal length, said extensions having threads cut thereon, and adapted to register with similar threads 115 interiorly cut in the outer end of said bonnet, and a cup shaped escutcheon holder, interiorly provided with threads, adapted to telescopically screw on to either end of said adjusting and stuffing gland, substantially 120 as and for the purpose set forth.

5. In a valve of the class described, the combination of a valve stem, a bonnet, a stuffing gland and a cup shaped escutcheon holder adapted to telescopically screw on to said stuffing gland for retaining the escutcheon in place and protecting the threads on the gland therefrom. 20
6. In a working unit for a valve of the class described, the combination of a bonnet, 10 a valve stem and a reversible adjusting and stuffing gland provided with extensions of unequal length. 25
7. In a working unit for a valve of the class described comprising in combination, 15 a bonnet and valve stem, a reversible stuffing gland and an escutcheon holder adapted to screw onto said stuffing gland.
8. In a bath fixture valve, the combination of a valve body having a neck interior- 30

In witness whereof, I have hereunto subscribed my name to this specification in the presence of witnesses.
